(57) **CLAIM**

I claim the ornamental design for a charger for information terminals, as shown and described.

DESCRIPTION

FIG. 1 is a perspective view of a charger for information terminals according to my new design when closed;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view thereof, when charging a portable information terminal;

FIG. 9 is a side view thereof, when charging a portable information terminal; and,

FIG. 10 is an alternative front view thereof, when charging a portable information terminal in a position different from FIG. 8.
